UNITED STATES PATENT OFFICE.

JOSEPH F. STILLMAN, OF BROOKLINE, MASSACHUSETTS.

BONE-BLACK REVIVIFIER.

SPECIFICATION forming part of Letters Patent No. 350,170, dated October 5, 1886.

Application filed March 25, 1886. Serial No. 196,489. (No model.)

To all whom it may concern:

Be it known that I, JOSEPH F. STILLMAN, of Brookline, county of Norfolk, and State of Massachusetts, have invented an Improvement 5 in Bone-Black Revivifiers, of which the following description, in connection with the accompanying drawings, is a specification, like letters on the drawings representing like parts.

This invention has for its object to improve 10 the construction of apparatus for drying bone-black, whereby the aqueous vapor given off by the bone-black during the drying process is prevented from coming in contact with the main charge or mass of bone-black.

15 My invention is especially adapted for use in sugar-refineries, wherein the bone-black, after being used in the process of sugar-refining, is renewed or revivified.

The main object of this invention is to prevent 20 the aqueous vapor which is given off during the drying process from coming in contact with the main mass or charge of bone-black; and I accomplish my object by placing directly over the retorts in which the bone-black is dried a preferably inclined series of 25 plates provided with hoppers—one for each retort—said inclined plates forming the upper wall or cover of a chamber beneath, into which chamber rise the aqueous vapor and products 30 resulting from the combustion of organic matter contained in the bone-black, said vapor and the products of combustion being exhausted from said chamber through a suitable outlet in any usual or suitable manner.

35 My invention also has for its object to provide each retort with means by which the aqueous vapor and products resulting from the combustion of the organic matter contained in the bone-black may readily pass 40 from said retort throughout its length into the chamber referred to; and I accomplish this object by means of a sectional pipe placed in each retort, and having its upper section extended into the chamber for the reception of 45 the aqueous vapor, said pipe being made so that a passage or opening is left between each section for the more ready passage outward of said vapor.

50 My invention consists, essentially, of a combustion-chamber, one or more passages or chambers communicating with said com-

bustion-chamber, one or more retorts in said passages, and the chute F, to contain unrevivified bone-black, combined with a plate located above the retorts to form a chamber, 55 E, and hoppers projecting from said plate into said retorts, said chamber receiving the aqueous vapor and products of combustion arising from said retorts.

My invention also consists of a combustion-chamber, one or more passages communicating with said chamber, one or more retorts in each passage, and a preferably sectional pipe in each retort, combined with a plate located above the retorts and composed of sections, 60 each section having hoppers and a stud to engage a bracket on a girder supported on the wall of the kiln, and by which to lock and maintain the said sections in place.

My invention further consists of details to 70 be hereinafter described, and pointed out in the claims at the end of this specification.

Figure 1 is a vertical section of a sufficient portion of a bone-black-revivifying kiln to enable my invention to be understood, the combustion-furnace and drier being but partially shown to save space in the drawing, the central pipes being mostly in elevation. Fig. 2 is an enlarged longitudinal section of one of the plates which separate the mass of bone- 75 black from the retorts; Fig. 3, a top view of Fig. 2; Fig. 4, an enlarged sectional view of part of the pipe contained in the retorts, and Figs. 5 and 6 details to be referred to.

Inclosed within the walls A of the kiln are 80 a series of retorts, a, preferably of iron, and preferably arranged side by side in rows in a chamber or passage in communication with the fire-chamber a', a part only of which is shown in the drawings. Each retort a is for 85 a portion of its length, near the top, of larger diameter, thereby forming a flange, by which said retort is supported upon cross-pieces a'a'', which are themselves supported by the side walls of the kiln. The cross-pieces a'' also 90 rest upon cross-beams b, supported by the brick-work of the kiln, and each beam b supports a girder, b', upon which rests a flanged piece, b'', the long flange b'' of each piece extending into a retort, a. As shown in Fig. 1, 95 the retorts a are arranged in pairs, and the space between the said retorts, extending the 100

length of the passage or chamber, is provided with a cap, herein shown as a flange-piece, b^4 , one flange each of said piece being extended into a retort.

5 Above the retorts a , and in a chamber formed between the central and side walls, A , of the kiln, is placed a series of preferably inclined plates, m , provided each with openings c , and having at one end a stud, c' , (see Fig. 2,) which 10 engages a bracket, e' , to lock and maintain said plate in position, said bracket being attached to a girder, c^4 , supported upon the central wall A , as shown in Fig. 1, said plate forming a chamber, E , below it. Through 15 each opening c in the plates m is projected a hopper or chute, d , provided with a depending flange or lip, d' , (see Fig. 6,) which fits into a groove, d^2 , in the plate m , about the opening c , such construction forming a seal to 20 prevent the passage of bone-black into the chamber E . The girder c^4 , as herein shown, supports the inclined bottom of a bone-black chute, F , in which the bone-black to be revivified is placed, and from which said bone-black runs through the outlet g down upon the plate m , and through the hopper d into the 25 retort with which the hopper is connected.

Within each retort a is placed a pipe, B , composed of superimposed sections g' , each section being cut away, as at g^2 , to form exhaust-passages for the aqueous vapor and products of combustion arising from the burning of the organic matter which has previously been absorbed by the bone-black from the sugar-solution as the latter was passed through said bone-black. Each section g' is provided with an outwardly-projecting lip, g^4 , upon which the bone-black strikes as it runs from the hopper d into the retort, said flange preventing the 40 bone-black from entering the pipe B . The superimposed sections g' , composing the pipe B , are each provided with a diametrical cross-bar, h' , having a central opening, through which a rod, h , is extended, said rod having a nut, h^2 , 45 at its top and bottom, by which the sections are firmly united together, to thus constitute a single pipe, as shown in Fig. 1, the upper section of each being herein shown as provided with a flange, h^3 , which serves as an additional 50 support for said pipe.

Instead of using the nut h^2 , the rod h may have a slot, through which to insert a pin.

The organic matter and water contained in the bone-black are given off as gases and vapor 55 when the bone-black is subjected to heat in the retorts, said gases and vapor passing up into the pipe B through the openings or passages g^2 , and from said pipe the gases and vapor issue into the chamber E , from which they are exhausted by any suitable means through the outlet h . The gases and vapor as they pass through the chamber E meet the under side of the plates m , heating the said plates, and thereby effect a partial drying of the bone-black upon the 65 upper surface of said plates, said partial drying expediting the operation in the retorts.

As fast as the bone-black has been revivified it is removed from the retort at its bottom in usual manner, and a fresh quantity of unrevivified bone-black descends by gravity into 70 the retorts a through the hopper d .

The plates m , which prevent the gases and vapor issuing from the pipes B from coming in contact with and being absorbed by the main mass of bone-black above them, are made 75 in sections, as shown, in order to readily gain access to the retorts. Each section-plate is provided at its sides with flanges m' , which enter a trough-shaped girder, m^2 , one end of which rests against the girder c^4 and the other upon 80 the flanged piece b^2 , as shown in Fig. 1, said trough-shaped girder forming a seal to prevent the bone-black from entering the chamber E .

The construction of the plates m , as shown, permits of ready access to the retorts when it 85 is desired to make repairs either to the pipe B or to the retort itself.

I claim—

1. In a kiln for revivifying bone-black, the combustion-chamber, one or more passages or 90 chambers communicating with said combustion-chamber, one or more retorts in said passages, and the chute F , to contain unrevivified bone-black, combined with a plate located above the retorts to form a chamber, E , and 95 hoppers projecting from the said plate into said retorts, said chamber receiving the aqueous vapor and products of combustion arising from said retorts, substantially as described.

2. In a kiln for revivifying bone-black, the combustion-chamber, one or more passages or chambers communicating with said combustion-chamber, one or more retorts in said passages, a pipe in each retort, and the chute F , to contain unrevivified bone-black, combined 100 with a plate located above the retorts and provided with hoppers projecting into said retorts, a chamber, E , being left below the said plate and above said retorts, said chamber receiving the aqueous vapor and products of 105 combustion arising from said retorts, substantially as described.

3. In a kiln for revivifying bone-black, the combustion-chamber, one or more passages or chambers communicating with said combustion-chamber, one or more retorts in said passages, a sectional pipe in each retort, and the chute F , to contain unrevivified bone-black, combined with a plate located above the retorts and provided with hoppers projecting into 110 said retorts, a chamber, E , being left below the said plate and above said retorts, said chamber receiving the aqueous vapor and products of combustion arising from said retorts, substantially as described. 115

4. In a kiln for revivifying bone-black, the combustion-chamber, one or more passages or chambers communicating with said combustion-chamber, one or more retorts in said passages, a sectional pipe in each retort, and the 120 chute F , to contain unrevivified bone-black, combined with a sectional plate located above 125

the retorts and provided with hoppers projecting into said retorts, a chamber, E, being left below the said plate and above said retorts, said chamber receiving the aqueous vapor and products of combustion arising from said retorts, substantially as described.

5. In a kiln for revivifying bone-black, the combustion-chamber, one or more passages communicating with said chamber, and the retorts *a* in each of said passages, combined with the plate composed of sections *m*, each section having a stud, *c*, and one or more openings, *c*, to receive a hopper, *d*, and with the girder *c'*, having the bracket *c''*, to be engaged by the 15 stud *c'*, to lock and maintain the section *m* in place, substantially as described.

6. In a kiln for revivifying bone-black, the combustion-chamber, one or more passages communicating with said chamber, the retorts 20 *a* in each of said passages, and the plate located above said retorts and composed of sections *m*, provided with flanges *m'*, combined with the girder *m'*, adapted to receive a flange, *m'*, of each of two contiguous sections and form a

seal for said plate, as and for the purpose set 25 forth.

7. The pipe B, composed of superimposed sections provided each with a projecting lip and passages *g*², combined with the rod *h*, extended through said pipe, and provided with 30 means, substantially as described, at its top and bottom to unite said superimposed sections, as and for the purpose set forth.

8. The pipe B, composed of superimposed sections provided each with projecting lip and 35 passages *g*² and cross-bar *h'*, having an opening, combined with the rod *h*, provided with means, substantially as described, at its top and bottom to unite said superimposed sections, as and for the purpose set forth.

In testimony whereof I have signed my name to this specification in the presence of two subscribing witnesses,

JOSEPH F. STILLMAN.
